DESIGN FOR A SERVICE PICTURE FRAME

Charles F. Cusick, New York, and Philip Marraccini, Bronx, N. Y.

Application October 23, 1942, Serial No. 108,600
Term of patent 3½ years

To all whom it may concern:

Be it known that we, Charles F. Cusick and Philip Marraccini, both citizens of the United States, residing at New York, and the Bronx, New York, in the county of New York and Bronx, respectively, and both in the State of New York, have invented a new, original, and ornamental Design for a Service Picture Frame, of which the following is a full, clear and exact description, reference being had to the accompanying drawing, forming a part thereof.

In the drawing:

Fig. 1 is a front elevational view of a service picture frame, showing our new design.

Fig. 2 is a side elevational view thereof.

We claim:

The ornamental design for a service picture frame, as shown.

CHARLES F. CUSICK.
PHILIP MARRACCINI.
